UNITED STATES PATENT OFFICE.

ALDEN L. PUTNAM, OF DETROIT, MICHIGAN, ASSIGNOR TO DETROIT PRESSED STEEL COMPANY, OF DETROIT, MICHIGAN, A CORPORATION OF MICHIGAN.

DESIGN FOR A VEHICLE-WHEEL BODY.

54,225.

Specification for Design.

Patented Nov. 18, 1919.

Application filed April 14, 1917. Serial No. 162,196. Term of patent 14 years.

To all whom it may concern:

Be it known that I, ALDEN L. PUTNAM, a citizen of the United States of America, residing at Detroit, in the county of Wayne and State of Michigan, have invented a certain new, original and ornamental Design for a Vehicle-Wheel Body, of which the following is a specification, reference being had

therein to the accompanying drawings, forming part thereof in which the design is shown in perspective.

I claim:

The ornamental design for a vehicle wheel body, substantially as shown.

ALDEN L. PUTNAM.
